UNITED STATES PATENT OFFICE

157,561

AUTOMOBILE SEAT COVER

Nathan Bloomfield, Chicago, Ill.

Application March 9, 1949, Serial No. 1,308

Term of patent 3½ years

(Cl. D14—6)

To all whom it may concern:

Be it known that I, Nathan Bloomfield, a citizen of the United States and a resident of Chicago, in the county of Cook and State of Illinois, have invented a new, original, and ornamental Design for an Automobile Seat Cover, of which the following is a specification, reference being had to the accompanying drawing, forming a part thereof, and in which:

Fig. 1 is a front elevational view of an automobile seat cover, showing my new design;

Fig. 2 is a rear elevational view thereof;

Fig. 3 is a side elevational view thereof.

I claim:

The ornamental design for an automobile seat cover, as shown.

NATHAN BLOOMFIELD.
